Primary Examiner — Barbara Fox*Assistant Examiner* — Aram Kwon(74) *Attorney, Agent, or Firm* — Amin, Turocy & Watson, LLP(57) **CLAIM**

The ornamental design for a speaker for cars, as shown and described.

DESCRIPTION

FIG. 1 is a front perspective view of a speaker for cars showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right-side elevational view thereof; and,

FIG. 7 is a left-side elevational view thereof.

The broken lines represent portions of the speaker for cars that are not part of the claimed design.
